United States Patent Office

Des. 181,407
Patented Nov. 12, 1957

181,407

BUDGET PLANNER OR SIMILAR ARTICLE

William G. Chamberlin, Cedar Rapids, Iowa, assignor to
Amana Refrigeration, Inc., Amana, Iowa, a corpora-
tion of Iowa

Application October 17, 1955, Serial No. 38,405

Term of patent 14 years

(Cl. D52—1)

FIG. 1

FIG. 2

FIG. 3

Figure 1 is a front elevation of a budget planner or similar article showing my new design;

Figure 2 is a rear elevation thereof;

Figure 3 is a fragmentary side elevation thereof taken substantially on line 3—3 of Figure 1.

I claim:

The ornamental design for a budget planner or similar article, substantially as shown.
